UNITED STATES PATENT OFFICE

2,090,580

CABLE ANCHORAGE AND ITS
INSTALLATION

James Forrest Howe, Worcester, Mass., assignor
to The American Steel and Wire Company of
New Jersey, a corporation of New Jersey

Application February 9, 1933, Serial No. 656,039

9 Claims. (Cl. 14—21)

This invention relates to multiple strand cable anchorages, one of the objects being the provision of a simplified apparatus. Other objects may become apparent later.

Generally speaking, the new anchorage consists of a plurality of structural shapes, interfastened in parallel spaced relationship to provide a frame having slots proportioned to receive socketed cable strands and to bring their sockets into engagement with adjacent portions of the frame when tensions are applied.

Preferably, these shapes are interfastened in such a manner that the slots are initially open-ended, whereby installation of the socketed strands may be effected by sliding them laterally into place. During this operation, one side of the frame of shapes may be permanently fixed to the masonry or main anchorage which is to receive the cable tensions, and the other side may be temporarily mounted to hold the anchorage in place without interfering with its slots. This temporary mounting may be removed and a permanent mounting substituted.

The usual shims may be placed between the shapes and the engaging strand sockets. The shapes must provide considerable depth to withstand the applied stresses, and it is therefore possible to apply strand shoes to the sides or edges of the shapes opposite from those engaging the sockets. These strand shoes effectively take up the cable thrust caused by the angularity of the strands from their splay point to the shapes.

Referring to the accompanying drawings which illustrate one form of the invention:

Figure 1 is a side view.

Figure 2 is a rear view.

Figures 3 and 4 are, respectively, horizontal cross-sectional and front views of the strand shoes.

Figures 5 and 6 are, respectively, front and side views of a shim suitable for use with a strand socket.

In this form of the invention, structural shapes comprise channel-bars 1. Other structural shapes may prove suitable or even preferable to channels, although flanged shapes should generally prove most desirable.

These channels are interfastened at their bottoms by a pin 2 which passes through all the channels and secured by nuts 3. This pin also mounts eye-bars 4 which not only transmit the cable tensions to the main anchorage but also provide for the desired spacing of the shapes, because they are interposed therebetween.

Washers 4^a may be placed between the eye-bars 4 and the channels to provide better bearing surfaces.

The cable strands 5 may be laterally inserted in the open-ended slots provided by the construction as so far described, the slots being sufficiently narrow to bring the sockets 6, on the ends of these strands, into engagement with adjacent portions of the shapes. These portions are the shapes' sides or edges opposite the strands' extending portions. As these shapes are in the present instance flanged, it will be seen that firm bearing surfaces are provided these sockets. Obviously, bearing blocks or other separable, and consequently relatively fragile, parts are unnecessary.

In other words, the various strands pass completely between the shapes to the rear portions of the latter and the sockets transmit the strand tensions directly to these portions because the latter are too closely spaced to permit the sockets to longitudinally pass between them. The sockets are not buried within the shapes but are out in the open at the rear of the anchorage. Tension is transmitted to the entire anchorage and the latter, as is subsequently described, then transmits this tension by way of its upper and lower ends to the main anchorage.

During the installation of the strands 5, the structural shapes 1 are temporarily positioned by flat bars 7 that connect backwardly to a suitable support, which may be the main anchorage. These bars should be arranged so as not to cover up the open ends of the slots between the channels.

Conventional shims 6^a may be interposed between the channels and the engaging strand sockets where necessary to equalize the strand tensions. Otherwise, the sockets directly engage the channels.

When the various strands are all positioned, the temporary positioning bars 7 may be loosened and a pin 2^a, which is a duplicate of the pin 2, passed through the other ends of all the channels, thus closing the slots. Although not mentioned, it is of course to be assumed that the channels are properly apertured to permit the passage of these two pins. This latter pin is likewise secured in place by nuts 3^a, and mounts the eye-bars 4, which may be fixed to the main anchorage, and washers 4^a. That is, both ends of the channels are now similarly interfastened and assembled. Washers 4^a may also be interposed between the nuts 3^a and the channels, if desired.

When the installation is thus far completed,

it may prove desirable to strengthen the resulting frame by riveting or bolting bars 8 across the fronts and backs of the shapes. Preferably, two bars are fixed to both sides or edges of the shapes, one being above the strands and the other below in each instance.

Strand shoes 9 are preferably bolted to the sides or edges of the shapes opposite to those engaged by the strand sockets, so as to take up the strands' thrusts due to the angularity of their splay point to the shapes. These shoes are illustrated as each comprising a U-shaped member having a recess 9a which receives the strands 5 and is flared outwardly to prevent un- 15 due wear on the cable strands. The open face of the recess 9a is arranged away from the center line of the cable's splay point to prevent dislodgement of the cable strands.

The sockets 6 are illustrated as being square in shape, but it is to be understood that any conventional type or shape of socket might be used. It might also be noted that the channels 1 are arranged with their closed faces opposite each other. This is done only to simplify the construction and is not a necessary feature.

I claim:

1. A multiple strand cable anchorage including the combination of a frame providing a plurality of slots at least some of which are each proportioned to longitudinally receive a plurality of transversely extending strands but which are sufficiently narrow to prevent the transverse passage of sockets on the ends of these strands when the latter are tensioned, and means 30 for connecting said frame to a main anchorage, said frame being constructed so that the ends of said slots may be open at least during the installation of the anchorage.

2. A multiple strand cable anchorage including the combination of a frame providing a plurality of slots at least some of which are each proportioned to longitudinally receive a plurality of transversely extending strands but which are sufficiently narrow to completely prevent the transverse passage of sockets on the ends of these strands when the latter are tensioned, and means for connecting the portions of said frame adjacent the ends of said slots to a main anchorage, said frame and means being constructed and arranged so that the ends of said slots may be open during installation of the anchorage, whereby already socketed strands may be laterally received by said slots, and may be closed by said means upon completion of the 55 installation.

3. A multiple strand cable anchorage including the combination of a plurality of structural shapes, means for interfastening said shapes in laterally spaced parallel relationship to provide a plurality of slots and for connecting them to a main anchorage so that said slots are transverse to the strands to be anchored, and a plurality of socketed strands arranged transversely through said slots and extending completely 60 between said spaced shapes to the rear portions of the latter, said shapes being too closely spaced to permit the sockets on said strands to transversely pass therebetween.

4. A multiple strand cable anchorage including the combination of a plurality of structural shapes, means for interfastening the said shapes in laterally spaced parallel relationship to provide a plurality of slots and for connecting them to a main anchorage so that said slots are transverse to the strands to be anchored, and a plu-

rality of socketed strands arranged transversely through said slots and extending completely between said spaced shapes to the rear portions of the latter, said shapes being too closely spaced to permit the sockets on said strands to pass transversely therebetween and said shapes having flat facing portions and right-angularly flanged rear portions through which said sockets transmit the strand tensions to the anchorage. 5

5. A multiple strand cable anchorage including the combination of a plurality of structural shapes, means for interfastening said shapes in laterally spaced parallel relationship and for connecting them to a main anchorage, a plurality of socketed strands arranged transversely through said slots and extending completely between said spaced shapes to the rear portions of the latter, said shapes being too closely spaced to permit the sockets to transversely pass therebetween, and strand shoes applied to the front portions of said shapes and engaging said strands so as to take the thrust of the latter caused by their necessarily splayed relationship. 10

6. A multiple strand cable anchorage including the combination of a plurality of structural shapes, means for interfastening the said shapes in laterally spaced parallel relationship and for connecting them to a main anchorage, a plurality of socketed strands arranged transversely through said slots and extending completely between said spaced shapes to the rear portions of the latter, said shapes being too closely spaced to permit the sockets to pass transversely therebetween and said shapes having flat facing portions and right-angularly flanged rear portions through which the sockets on said strands transmit the strand tensions to the anchorage, and strand shoes applied to the front portions of said shapes and engaging said strands so as to take the thrust of the latter caused by their necessarily 20 splayed relationship. 25

7. A multiple strand cable anchorage including a frame made of a plurality of elongated members interfastened in parallel spaced relationship and means for mounting said frame transverse to socketed strands comprising one end of the cable to be anchored, said strands being arranged transversely between said members with their sockets behind the same, said members having flanges at their back edges and being spaced sufficiently to cause said sockets to be pulled into engagement with said flanges when said strands are tensioned. 30

8. A multiple strand cable anchorage including a frame made of a plurality of elongated members interfastened in parallel spaced relationship and means for mounting said frame transverse to socketed strands comprising one end of the cable to be anchored, said strands being arranged transversely between said members with their sockets behind the same, said members having flanges at their back edges and being spaced sufficiently to cause said sockets to be pulled into engagement with said flanges when said strands are tensioned, said members being interfastened by removable pin elements passed transversely through their respective ends to form said frame, whereby removal of one of said elements permits longitudinal insertion of said strands between said members. 40

9. A multiple strand cable anchorage including a frame made of a plurality of elongated members interfastened in parallel spaced relationship and means for mounting said frame transverse to socketed strands comprising one end 45

of the cable to be anchored, said strands being arranged transversely between said members with their sockets behind the same, said members having flanges at their back edges and being spaced sufficiently to cause said sockets to be pulled into engagement with said flanges when said strands are tensioned, said members being interfastened by removable pin elements passed

transversely through their respective ends to form said frame, whereby removal of one of said elements permits longitudinal insertion of said strands between said members, and the fronts of said members being provided with strand shoes which engage said strands. 5

JAMES FORREST HOWE.
